United States Patent Office.

FREDERIC J. PEABODY, OF MEDFORD, MASSACHUSETTS.

Letters Patent No. 80,563, dated August 4, 1868.

IMPROVEMENT IN BUTTONS.

The Schedule referred to in these Letters Patent and making part of the same.

TO ALL WHOM IT MAY CONCERN:

Be it known that I, FREDERIC J. PEABODY, of Medford, in the county of Middlesex, and State of Massachusetts, have invented an Improvement in Studs for Wearing-Apparel, of which the following is a full, clear, and exact description, reference being had to the accompanying drawings, making part of this specification, in which—

Figure 1 is a perspective view of a stud having my improvement applied thereto.

Figure 2 is a plan of the under side of the same.

Figure 3 is a side elevation of the same.

Figure 4 is a section on the line xx of fig. 2.

Studs for wearing-apparel have been constructed with a slit in the back or disk, extending from the circumference to the shank, one of the edges of the slit being raised with respect to the other, so that the stud could be turned into the button-hole in a manner similar to a screw. A stud constructed in this manner, although it may be easily inserted into the button-hole, is, nevertheless, objectionable, for the reason that an opening or break is left in the periphery of the back, and the raised edge of the slit is liable to catch in the edge of the button-hole, thus endangering the loss of the stud in the event of its being accidentally turned backward by the movements of the wearer.

My invention has for its object to overcome this objection, and consists in a stud, the back or inner plate of which is divided on one side into two portions, which are bent or curved around in opposite directions, so as to overlap each other for a considerable distance, leaving no opening or break in the periphery of the inner plate, and avoiding the danger of loss incident to studs constructed as first described.

To enable others skilled in the art to understand and use my invention, I will proceed to describe the manner in which I have carried it out.

In the said drawings, A represents the front portion or face of a stud, from which projects the shank a , to which is attached the back or inner plate B. This plate is divided on one side into two portions, b c , which are bent or curved around in opposite directions, and are of a sufficient length to overlap each other for a considerable distance, thus forming a portion of a screw, as seen in fig. 3, the two portions b and c lying close to each other, so as not to materially increase the thickness of the plate B.

When the stud is to be applied to a garment, the point of the curved portion b of the plate B is inserted into the button-hole, and the stud turned until the whole plate has passed through to the other side, when it will be securely fastened in place, and as the line of the periphery of the inner plate B is unbroken, and the point of the portion c lies close to this plate B, there is little or no liability of the stud becoming accidentally detached from the garment, and my improvement is therefore applicable to studs and buttons of great value, which has not been the case with devices containing the screw-principle as heretofore constructed.

I am aware that the back of a stud has been constructed with a slit, extending from its circumference to the shank, so that the stud could be turned into the button-hole in a manner similar to a screw, and also that a stud has been provided with a wire shank extending from its centre, and bent around in a helix or spiral form. I therefore lay no claim to these features; but

What I do claim as my invention, and desire to secure by Letters Patent, is—

A stud or button, having its back or inner plate B divided on one side into two portions, b c , which are bent or curved around in opposite directions, so as to overlap each other, substantially in the manner and for the purpose set forth.
